BOILER WATER FEED DEVICE

Thomas N. Pinion, Denver, Colo.

Application April 11, 1944, Serial No. 530,512

17 Claims. (Cl. 122—456)

1

This invention relates to boiler water feed devices adapted to supply water to and during the operation of boilers employed for the generation of steam, and more particularly to such devices arranged for the automatic maintenance of a given level of water within the associated boiler, and has as a primary object to provide an improved unitary device of the character described susceptible of fully automatic and continuous operation in association with a steam boiler of any type to maintain the desired predetermined level of water within such boiler.

A further object of the invention is to provide an improved boiler water feed device responsive to lowering of the water level in its associated boiler below a predetermined plane to automatically feed additional supplies of water into said boiler against the steam pressure therein until the boiler water level is reestablished at the desired predetermined plane.

A further object of the invention is to provide an improved boiler water feed device automatically operable to maintain a predetermined level of water within its associated boiler through the agency of the boiler steam pressure assisted solely by a water supply pressure materially less than the boiler pressure.

A further object of the invention is to provide an improved boiler water feed device including improved means for balancing internal boiler pressure against a supply of feed water so that the latter may flow by gravity to seek and establish its level within the boiler.

A further object of the invention is to provide an improved operative combination of heat-responsive means in actuating relation with control valve elements to position said elements for steam flow and pressure control within and through a water feed device in response to water level changes within an associated boiler.

A further object of the invention is to provide improved heat-responsive, steam-actuated means for repetitively charging a feed water reservoir from a feed water supply and emptying said charged reservoir into an associated boiler against the internal boiler pressure in response to a lowering of the water level within said boiler below a predetermined plane.

A further object of the invention is to provide an improved combination with a heat-responsive, steam-actuated boiler water feed device of auxiliary heat-responsive, steam-actuated means operable to continue the functioning of the device upon, and to warn of, failure in the normal

10 operation of the principal control means of the assembly.

With the above principal, and other more detailed, objects in view, my invention consists in the construction, arrangement, and combination of elements hereinafter set forth, pointed out in my claims, and illustrated by the accompanying drawings, in which—

Figure 1 is a cross section taken vertically and axially through a conventionalized embodiment of my improved device with the control elements thereof positioned for flow of feed water to an associated boiler. Figure 2 is a view similar to Figure 1 illustrating the relative positions of the control elements in their cyclic operative phase next subsequent to that exemplified in said Figure 1. Figure 3 is a view similar to Figure 2 illustrating the relative positions assumed by the control elements in that phase of their operative cycle subsequent to the showing of Figure 2. Figure 4 is a view similar to Figure 3 illustrating the relative positions of the control elements in the final phase of their operative cycle and just prior to their return to the positions shown in Figure 1. Figure 5 is a fragmentary, detail section axially through the compound valve assembly in the relationship of elements shown in elevation in Figure 1. Figure 6 is a fragmentary detail section through and illustrating an alternative operative position of elements within control means actuatable by the auxiliary heat-responsive means associated with the device. Figure 7 is a fragmentary, detail section, on an enlarged scale, taken on the indicated line 7—7 of Figure 2. Figure 8 is a fragmentary, detail section, on an enlarged scale, illustrating more in detail the operative relationship of relatively movable elements of the compound valve assembly as shown in Figure 4. Figure 9 is a plan view, partly in section and on a reduced scale, of the assembled device as viewed from the plane indicated by the line 9—9 of Figure 3, certain connections being omitted for the sake of clarity. Figure 10 is an elevation of the improved device 20 as associated and operatively related with a conventional boiler for practical use.

In the construction of the improvement as shown, the numeral 10 designates a preferably cylindrical housing defining and enclosing a relatively large chamber or reservoir adapted to receive and accumulate a charge of boiler feed water. The housing 10 is closed to communication with the atmosphere except as hereinafter specifically provided, is adapted for disposition with its axis substantially vertical and in such

definite altitudinal relation with the desired water level of the boiler to be served thereby as is hereinafter set forth, and is constructed to accommodate and withstand the operating pressures of the boiler with which it is associated. The top and bottom closures of the housing 10 are preferably substantially plane, parallel, and perpendicular to the housing axis, and said closures are intersected by a straight, tubular, valve barrel 11 coaxial with said housing and extending through and equally at each end beyond said closures. The outer ends of the barrel 11 are closed by suitable cap elements 12 through each of which a branch 13 from a steam line 14 communicates to include the opposite end portions of the barrel 11 in a flow circuit common to both. A second steam line 15 is suitably sealed through the top closure of the housing 10 and communicates through a wall of the barrel 11 at a point midway between the top and bottom housing closures, and communication between the barrel interior and the reservoir defined by the housing 10 is provided by a plurality of ports 16 intersecting the barrel wall just beneath the housing top closure and by a similar series of ports 17 intersecting the barrel wall just above the housing bottom closure.

The barrel 11 serves as a mounting and slide bearing for a pair of double-spool valves 18 closely fitted for axial reciprocation therein. The valves 18 are identical in construction and are disposed in opposition within the barrel 11. Each of the valves 18 is a unitary, cylindrical member of considerable length formed with an enlarged, annular head 19 at each of its ends for close-fitting, slidable engagement with the barrel walls, and with an annular rib 20 intermediate the heads 19 for like sealing reciprocation within the barrel, the heads 19 and ribs 20 preferably being provided with suitable packing or sealing rings 21 to minimize leakage of pressures or fluids between said elements and the adjacent barrel walls. The body portions of the valves 18 between their rib 20 and heads 19 are reduced in diameter to provide annular chambers defined between the valve body, rib 20, respective head 19 and corresponding portion of the barrel walls. Opposed inner heads of the valves 18 are provided with axially-projecting studs or bosses 22 adapted to engage when the valves are moved inwardly of the barrel towards each other and arrest such valve travel with a space separating the adjacent inner valve heads.

A steam line 23 opens through the wall of the upper extension of the barrel 11 just above the top closure of the housing 10 and connects with the steam dome 101 of the boiler 100 to be served in such manner as to deliver steam at boiler pressure to said upper barrel extension, and a water line 24 opens through the wall of the lower barrel extension just below the bottom housing closure and connects with the boiler 100 to be served at some convenient point below the normal water level therein. The valves 18 control the admission of steam to and the escape of feed water from the reservoir defined by the housing 10 and to that end the lengths of said valves and the positions of the ribs 20 therealong are so adjusted as to provide that, when the valves are at the inner limit of their range of travel with their studs 22 engaged, as shown in Figures 1 and 2, the said ribs 20 will be positioned inwardly of the barrel from and in uncovering relation with their respective ports 16 and 17 while the outer heads 19 of said valves will be disposed

outwardly of the barrel from and in uncovering relation with the ends of the respective lines 23 and 24, so that steam from the line 23 may enter the annular chamber about the outer body portion of the upper valve 18 between the outer head 19 and rib 20 thereof and thence escape through the ports 16 into the upper portion of the housing 10, while water accumulated within said housing may pass through the ports 17, into the annular chamber about the outer portion of the lower valve 18 between the outer head 19 and rib 20 thereof and thence through the pipe 24 to the boiler; while, when said valves 18 are at the outer limit of their range of travel, at their position of maximum separation with their outer heads 19 engaging the caps 12 of the barrel 11, as shown in Figures 3 and 4, the ribs 20 of said valves engage the barrel walls in obstructing relation between their respective flow lines and ports and thereby inhibit inflow of steam to and outflow of water from the housing interior.

Positioning of the valves 18 at either extreme of their range of travel is automatically controlled through means and agencies hereinafter described which act to alternatively admit steam to mid or end portions of the barrel 11 through the line 15 or line and branches 14, 13, it being obvious that when steam is admitted through the line 15 to the space between the inner heads 19 of the valves 18, the line 14 and its branches 13 being open to exhaust, the said valves 18 act as pistons within the barrel 11 and are moved apart to the outer limit of their range of travel, while when steam from the line 14 is admitted through the branches 13 simultaneously to the outer end portions of the barrel 11, the line 15 being open to exhaust, the said valves again function as pistons and are moved inwardly of the barrel to the inner limit of their range of travel with their studs 22 engaged. To insure proper positioning of the valves 18 at the inner limit of their range of travel and to prevent possible overtravel of one of said valves, it may be desirable to provide a suitable stop, such as an inward projection of the line 15 within the barrel, beyond which neither valve may pass.

Control of the admission of boiler feed water to the interior of the housing 10 and automatic positioning of the valves 18 is largely the function of a multiple, compound, thermostatically-actuated valve assembly operatively housed in a tubular slide chamber 25 disposed in spaced, axially-parallel relation with the barrel 11 in or as an enlargement of one side of the housing 10. The lower end of the slide chamber 25 is closed by a plug, or similar element, 26 having an inner surface substantially coplanar with that of the housing bottom closure, and the upper portion of said chamber 25 projects through and above the housing top closure, wherethrough it is suitably sealed, and has its upper end suitably closed by means of a cap 27. Communication between the interior of the housing 10 and the bore of the slide chamber 25 is provided at two points, one or a series of ports 28 opening through the wall of said chamber dividing it from the housing reservoir just below the housing top closure and one or a series of ports 29 opening through said chamber wall in somewhat spaced relation above the housing bottom closure. A stud or post 30 is fixed centrally of and rises axially from the inner, upper surface of the plug 26 and extends upwardly within the lower portion of the chamber 25 to a point somewhat above the port or ports 29, and said post 30 serves as a base

and support for a quick-acting, thermostatic element 31 which is secured at its lower end to the upper end of said post and rises thereabove centrally within the chamber 25; said element 31 being constructed and arranged for expansion when subjected to higher temperatures, and consequent upward projection of its upper end away from the post 30, and for retraction when subjected to lower temperatures, with consequent downward travel of its upper end towards said post.

A plurality of pipes or tubes 32 connect through the plug 26 to open into the annular space between the post 30 and wall of the chamber 25 at the lower end of the latter, and said pipes 32 operatively connect at their lower ends, as through a common fitting 33, with a water supply line 34, leading to said fitting 33 from a suitable source of boiler feed water (not shown) so that water for boiler feed may be fed through the line 34, fitting 33 and pipes 32 to and within the lower end of the chamber 25 and thence through the port or ports 29 to the reservoir defined by the housing 10. The improved boiler water feed apparatus is not of pump or suction type, hence it is essential for successful operation of the apparatus that the boiler feed water be fed to and through the supply line 34 under such degree of pressure as will serve to insure flow within the housing 10 against normal atmospheric pressure, and since many agencies, such as elevated tanks, pumps, air pressure systems, and public water supply systems, are commonly available and have been heretofore generally used for the same and analogous purposes, no showing or description of means for the supply of water under pressure to and through the line 34 is deemed necessary herein. Similarly, while the improved apparatus will operate to feed water delivered thereto as a fluid at any temperature below the vaporizing point, it has long been common practice to preheat boiler feed water and many agencies and devices are available and in common use for such purpose, hence, since the practicability of the improved device is enhanced by preheating of the boiler feed water, it will be assumed that the supply thereof fed to and through the line 34 is at a temperature raised above the normal range.

As is usual practice, the supply line 34 is provided with a check-valve 35 at some distance from its connection with the fitting 33, so as to inhibit reverse flow of water within said line, and flow of water through said line 34 to the chamber 25 and housing 10 is automatically controlled by a pressure-responsive valve 36 in said line between the fitting 33 and check-valve 35. The valve 36 may be of any specific type and construction suitable to its purpose and mode of actuation, and is conventionally illustrated as comprising a fitting wherein a plug 37 is slidable radially and inwardly to obstruct flow through the fitting and radially and outwardly to permit flow through said fitting, the outer end of said plug 37 entering a pressure chamber 38 divided by a diaphragm 39 and centrally engaging said diaphragm, which is normally urged, by means of a spring 40, into unflexed dividing relation with the chamber 38 and consequent flow-permitting relation of the plug 37 within its fitting. The portion of the pressure chamber 38 on the side of the diaphragm opposite the plug 37 is connected by means of a flow line 41, through the cap 27, with the interior of the upper end of the slide chamber 25, so that fluid pressures of sufficient

magnitude present in the upper end of said slide chamber may, by transmission through the open flow line 41, act within the chamber 38 to flex the diaphragm 39 and move the plug 37 into flow-obstructing relation with its fitting, and thus close the valve 36 against flow through the line 37; escape or relief of the so-acting pressures at the chamber 25 operating to correspondingly relieve the pressure within the chamber 38 for consequent return of the plug 37 to flow-permitting position. Since, under certain operating conditions of the improved apparatus, water retained in the line 34, fitting 33, pipes 32 and lower portion of the chamber 25 may adversely affect actuation of control elements of the apparatus when the valve 36 is closed, means is provided for automatically returning a portion of such retained water to the flow line 34 behind the check-valve 35, at times; such means comprising a water flow line 42 connecting at one end with the supply line 34 behind the check-valve 35 and at its other end with said supply line between the fitting 33 and valve 36, thus by-passing the valves 35 and 36, and a pressure-responsive valve 43 controlling communication between the lines 34 and 42 where the latter meets the former between the valve 36 and fitting 33. The valve 43 may conveniently be of the same type and general construction as the valve 36, and is so shown, the diaphragm-actuating pressure chamber portion of the valve 43 being connected by means of a branch or extension 41' with the flow line 41, but the valve 43 differs in operative character from the valve 36 in that the flow-controlling plug 37' of the former is arranged to obstruct flow between the lines 42 and 34 when there is no fluid pressure in the flow line 41 and to open for flow communication between said lines 42 and 34 when there is pressure in the line 41, so that, responding to the same control, presence or absence of pressure in the line 41, the valve 43 is open when the valve 36 is closed and the valve 43 is closed when the valve 36 is open, there hence being no water flow in either direction through the by-pass line 42 when the line 34 is open to supply feed water to the chamber 25 and housing 10.

The portion of the slide chamber 25 above the thermostatic element 31 slidably accommodates and is substantially filled by an integral, multiple-spool type, cylindrical valve unit 44 closely fitted within the bore of said chamber and disposed for limited axial reciprocation therein. A plurality of legs 45 are fixed to and depend in circumferentially-spaced relation from the lower end of the valve unit 44 and freely traverse the space between the walls of the chamber 25 and the element 31, preferably in somewhat spaced relation inwardly from the chamber walls, and fixedly engage at their lower ends with an annular plate 46 slidably engaging about the post 30 and substantially filling the space between said post and the adjacent walls of the chamber 25 at the lower end of the latter. The plate 46 is adapted to engage with its plane lower surface against the upper face of the plug 26 and close over the upper, otherwise open ends of the pipes 32, at times, and the thickness of the plate 46, length of the legs 45, and length of the valve unit 44, are so proportioned as to position the lower end of said valve unit in spaced relation above the upper end of the contracted thermostatic element 31, and the upper end of said valve unit in spaced relation below the lower surface of the cap 27, when said plate 46 engages the upper surface of the plug 26, as is shown in Figures 1 and 2, and to

position the lower surface of said plate 46 above the upper margin of the port or ports 29 when the upper end of the valve unit 44 is in engagement with the lower surface of the cap 27, as is shown in Figures 3 and 4, said two positions of the valve unit 44 and its attached elements being the two operative positions and reciprocative limits of the unit.

The valve unit 44 is divided by means of four exterior annular grooves or zones of reduced diameter into five spaced sections of full diameter adapted to closely fit within and slidably engage the walls of the slide chamber 25, said sections being respectively designated from bottom to top of the valve unit by the reference numerals 44a, 44b, 44c, 44d and 44e, and the zones of reduced diameter, each of which defines an annular compartment between the chamber walls, valve unit surface, and adjacent valve unit sections, are respectively designated by the indicia A, B, C and D. The zones of reduced diameter may be uniform in depth radially of the valve unit 44, but they are not uniform in length axially of said valve unit, and the valve unit sections set off thereby are not necessarily uniform in dimension axially of the valve unit, the relative size and relationship of said zones and sections being determined by considerations of operative position and relationship, as will hereinafter appear. To enhance engagement of the valve unit sections against the walls of the chamber 25 in a manner to minimize leakage of fluid pressures therebetween, the peripheries of said sections may each be provided with one or more compression or sealing rings, as is common practice.

The wall portion of the slide chamber 25 extending above the housing top closure is intersected at five altitudinally-spaced points by flow lines which open through the chamber walls for communication with the chamber bore, said flow lines being, in their altitudinal order from the top of the slide chamber downward, a steam supply line 47 arranged, through valve fittings and connections hereinafter to be described, to supply steam at boiler pressure from the steam dome 101 at a point somewhat below the upper end of the valve unit 44 when the latter is at the lowermost limit of its range of reciprocation; one end of the steam line 14, which opens into the chamber 25 at a point somewhat below the connection with the line 47; an exhaust line 48 intersecting the chamber wall at a point below the connection with the steam line 14; the end of the steam line 15 exterior to the housing 10, which line opens into the chamber at a point below that of communication with the exhaust line 48; and a branch steam supply line 49 leading from the supply line 47 to open into the chamber just above the housing top closure and at a point below the connection with the line 15. These connections and their altitudinal relationships determine in large measure the relationships and dimensions axially of the valve unit 44 of the valve unit sections 44a, 44b, 44c, 44d and 44e and of the compartments A, B, C and D. The valve unit section 44a constitutes the lower end portion of the valve unit 44 and is limited in upward extent by the zone of reduced diameter forming the compartment A which separates said first section from the second section 44b in such manner as to position the latter across and in complete obstructing relation with the port or ports 29; said section 44b having an axial length sufficient when the valve unit 44 and attached elements is at the lower limit of its range of

travel, as shown in Figures 1 and 2, to fully cover and close said port or ports. The valve unit section 44c is spaced from the section 44b by the zone of reduced diameter forming the compartment B in such manner as to position the section 44c as a baffle between the opening ends of the lines 15 and 48, so that the line 49 opens below the section 44c into the compartment B, which is otherwise closed, and the line 15 opens above the section 44c and into the lower portion of the compartment C, according to the showing of Figures 1 and 2. The axial length of the zone of reduced diameter forming the compartment C is such as to position the valve unit section 44d as a baffle between the opening ends of the steam line 14 and the exhaust line 48, so that said latter line opens into the upper end of the compartment C below the section 44d and the line 14 opens into the lower portion of the compartment D above said section, again referring to the position of the elements shown in Figures 1 and 2, and communication is thus established between the line 15 and exhaust line 48, through the compartment C. The end zone of reduced diameter forming the compartment D is of such axial length as to position the upper end valve unit section 44e just above the opening end of the steam supply line 47 and as a baffle closing away the compartment D from communication with the space in the slide chamber bore between said section 44e and the chamber cap 27, so that the lines 47 and 14 both open into the compartment D when the valve unit is in the position shown in Figures 1 and 2 and thus provide a continuous passage for steam from said line 47 through the compartment D and into the line 14. Thus, with the elements of the valve unit 44 in the position shown in Figures 1 and 2, the plate 46 is closed over and against the upper ends of the pipes 32; the port or ports 29 is closed by the section 44b; inflow of steam through the branch 49 is arrested and confined in the compartment B by the sections 44b and 44c; communication for flow from the line 15 to the line 48 is established through the compartment C; and communication for inflow of steam from the line 47 to the line 14 is established through the compartment D.

Referring now to the connections and relationships established by the valve unit 44 and its associated and attached elements when said body is moved, by means and agencies operating in a manner hereinafter to be described, to the upper limit of its range of reciprocation and to the position shown in Figure 3, it will be seen that the relative size, disposition and relationship of the valve unit elements and attachments hereinabove set forth is such as to position the plate 46 above and in unobstructing relation with the port or ports 29; to dispose the compartment A in registration with the port or ports 29 and in communication, through the latter, with the interior of the housing 10; to position the section 44b below the opening end of the line 15, so that a passage for inflow of steam from the line 49 to the line 15 is provided through the compartment B; to dispose the compartment C in simultaneous communication with the opening ends of the lines 14 and 48, so that a passage to exhaust is opened from the line 14 to the line 48 through said compartment C; and to dispose the section 44d as a baffle between the opening ends of the lines 14 and 47, thereby inhibiting delivery of steam from the line 47 to the line 14 and limiting such steam delivery from said line 47 to the compartment D whereinto said line 47 opens.

One other connection with the bore of the slide chamber 25 is important to operation of the apparatus, and such connection takes the form of a water line 50 adapted to deliver water, under suitable pressure and at temperatures at or below normal, from any suitable source and through any suitable means and agencies, to the lower portion of the slide chamber bore above and adjacent the the upper end of the retracted thermostatic element 31, the discharge end of said line 50 opening through the slide chamber wall just above the lower end of the valve unit section 44a when the valve unit 44 is at the lower limit of its range of reciprocation, as shown in Figures 1 and 2, and in position to be covered and obstructed by said section 44a when the plate 46 is seated against the plug 26, which arrangement locates the discharge end of said line 50 to be uncovered and free for delivery of water to the slide chamber bore when the valve unit 44 is moved to the other limit of its range of reciprocation, as shown in Figures 3 and 4.

The valve unit 44 is longitudinally traversed by an axial bore which opens through both ends of said body and includes portions of lesser and greater diameters providing a shoulder 51 where they meet. The bore portion of lesser diameter traverses the lower portion and opens through the lower end of the unit 44 and the bore portion of greater diameter traverses the upper portion and opens through the upper end of said valve unit, and the shoulder 51 is disposed in approximately the plane of the upper margin of the valve unit section 44c. The bore just above described houses and slidably mounts for limited axial reciprocation a two-diameter, cylindrical valve element 52, whereof the portions of different diameter fit closely and slidably within the bore portions of corresponding size. The portion of the valve element 52 of greater diameter is designated 52a and is adapted to slidably telescope within the upper, greater-diameter portion of the bore within the valve unit 44 and be thus positioned interiorly of and for limited axial reciprocation relative to the portions of the valve unit forming the compartments C and D, while the valve element portion of lesser diameter is designated 52b and is shown as adapted to slidably engage within and through the lower, lesser-diameter portion of the valve unit bore for limited axial reciprocation relative to and interiorly of the valve unit portions forming the end section 44a and the compartments A and B. The shoulder 52c formed at the junction of the valve element portions 52a and 52b is adapted to engage at times against the shoulder 51 of the valve unit 44 and limit relative travel of the element 52 downwardly of said valve unit, and the length of the valve element portion 52b is such as to provide an extension of said valve element portion, terminating in a head or exterior annular flange 53, axially of and outwardly beneath and beyond the lower end of the valve unit section 44a when the shoulders 51 and 52c are engaged and the element 52 is at the lower limit of its range of travel relative to the valve unit. The valve element head 53 is adapted to engage at times against the lower end of the element 52 relative to said valve unit, and the length of the element portion 52a is such as to bring its upper end into coplanar relation with the upper end of the valve unit 44 when said element 52 is at the upper limit of its range of travel within said valve unit. When the ele-

ment 52 is at the upper limit of its range of travel, as determined by engagement of the element head 53 against the lower end of the valve unit 44, the shoulders 51 and 52c are separated and then serve, together with the adjacent walls of the element portion 52b and valve unit bore, to define a compartment E interiorly of the valve unit and in position to communicate through ports 54, opening through the walls of the valve unit beneath the valve unit section 44d, with the compartment C. Since the length of the valve element portion 52a is such as to position the upper end of said portion in coplanar relation with the upper end of the valve unit 44 when the element 52 is at the upper limit of its range of travel relative to said valve unit, the upper end of said portion 52a is retracted within the valve unit bore when the element 52 is at the lower limit of its range of travel, such retraction serving to open and uncover ports 55, intersecting the valve unit walls just beneath the valve unit section 44e, to establish communication between the compartment D and the open upper end of the valve unit bore; it being obvious that the ports 55 are closed by the element portion 52a when the element 52 is at the upper limit of its range of reciprocation within the valve unit.

The valve element 52 is formed with upper and lower axial bore sections 56 and 57, respectively, separated by means of a baffle 58 obstructing said bore sections somewhat below the element shoulder 52c. The upper bore section 56 extends upwardly from the baffle 58 to open through the upper end of the element 52 and the lower bore section 57 extends downwardly from said baffle 58 to the head 53 closing the lower end of said element 52. Ports 59 intersect the walls of the valve element portion 52a just above the baffle 58, so that communication may be had therethrough between the lower end of the upper bore section 56 and the compartment E when the element 52 is at the upper limit of its range of reciprocation within the valve unit 44, and similar ports 60 intersect the walls of the element portion 52b just below the baffle 58 to establish communication between the upper end of the lower bore section 57 and the compartment E when the element 52 is positioned as above stated, the baffle 58 being hence so located in the element 52 as to lie above the shoulder 51 and thus permit uncovering of the ports 60 when the element 52 is in the relative position shown in Figures 2 and 3. Suitable ports 61 open through the lower end of the lower element portion 52b just above the head 53 and in position to be uncovered when the element 52 is at the lower limit of its range of reciprocation relative to the valve unit 44, and other ports or apertures 62 intersect intermediate portions of the walls of said element portion 52b in position to register with ports 63 in the valve unit walls between the valve unit sections 44a and 44b and thus establish communication between the bore section 57 and the compartment A when the element 52 is at the upper limit of its range of relative reciprocation.

The lower end of the valve element 52 bears against and is secured in any suitable manner to the upper end of the thermostatic element 31, thereby mounting said element 52 for axial displacement determined by expansion and retraction of the said element 31.

The elements thus far described, in the operative relationships set forth, constitute a fully automatic device operable to feed water to an op-

11

erating boiler 100 for maintenance of the water level in said boiler. The device, constructed and assembled as shown and described, is mounted in fixed position, with the axes of the barrel 11 and slide chamber 25 vertical, adjacent the boiler 100 to be served thereby and is so disposed altitudinally as to bring a horizontal plane intersecting the port or ports 29, indicated by the broken line L—L in Figure 1, into coincidence with the water level to be maintained in the boiler; the lines 23 and 47 are suitably connected with the steam dome 101 or other steam supply at the boiler; the line 24 is operatively connected with a supply of boiler feed water (preferably heated) under pressure, and the line 50 is connected with a pressure supply of unheated water; and so mounted and connected the device is ready for automatic operation.

Assuming as an initial condition that the reservoir defined by the housing 10 is substantially filled with feed water and that unheated water supplied through the line 50 has cooled and consequently contracted the thermostatic element 31 to permit positioning of the valve unit 44 and element 52 at the lower limit of their range of reciprocation, as shown in Figure 1. With the various elements positioned as shown in the figure last noted, steam at boiler pressure is supplied through the line 47 to compartment D whence it is free to pass through the now uncovered ports 55 and open upper end of the valve unit bore into the upper end of the slide chamber 25 and through the line 41 to the valve-actuating pressure chambers 38 where such pressure actuates the diaphragms 39 to close the valve 36 and open the valve 43, thus closing the line 34 and opening the by-pass 42, while the pressure thus developed within the upper end of the slide chamber acts against the upper ends of the valve unit 44 and against the upper ends of the valve element 52 to seat and hold said members at the lower limit of their range of reciprocation with the plate 46 closing over the upper ends of the pipes 32, the port or ports 29 open and unobstructed, the valve unit section 44b in closing relation with the port or ports 28, the ports 54, 59, 60 and 62 closed, and the ports 61 exposed and 63 and 64 closed, and the ports 61 exposed and opening into the slide chamber bore beneath the valve unit 44; flow through the line 50 being cut off by the valve unit lower section 44a. Since the line 14 and its branches 13 is now in communication with compartment D, steam from said compartment may and does flow through said line and branches to the opposite ends of the barrel 11, where the pressure of the steam acts to hold the spool valves 18 at the inner limit of their range of travel, with their studs 22 in end engagement, and in position to establish a path for steam flow from the line 23 through the ports 16 to the interior of the housing 10 above the level of the feed water therein, and a path of water flow outwardly from the housing through the ports 17 and line 24, any pressure-induced tendency of the valves 18 to separate being obviated by the communication between the line 15 and exhaust line 48 established through compartment C. Since the pressure on the water within the boiler 100 and on the feed water within the housing 10 is now balanced, the feed water in the housing 10, standing at a higher level than the water in the boiler, is free to flow into the boiler through the line 24 until the levels coincide.

When, due to transfer of feed water from the housing 10 to the boiler, the feed water level in the housing drops sufficiently to uncover a portion of the port or ports 29, steam from the hous-

12

ing enters the lower portion of the slide chamber 25 through the uncovered portion of said port or ports and acts, because of its high temperature, to expand the thermostatic element 31 with consequent upward travel of the upper end of said element and the valve element 52 associated therewith. As the valve element 52 starts its upward travel within the valve unit 44, the shoulders 51 and 52c separate to develop the compartment E and the ports 59 and 60 are uncovered and placed in communication with said compartment, thus establishing a vent passage from the lower end of the slide chamber 25, through ports 61, bore 57, ports 60, compartment E, ports 54, and compartment C, to exhaust line 48, so that any resistance to the flow of steam from the housing 10 into the lower end of the slide chamber is fully obviated; and at the same time an exhaust passage is established from the upper end of the slide chamber 25 through the bore 56, ports 59, compartment E, ports 54, and compartment C, to exhaust line 48, so that steam pressure previously obtaining in the upper end of said slide chamber may be relieved through such exhaust passage and resistance to upward travel of the valve unit 44 and element 52 minimized. Continuing expansion of the element 31 operates to move the element 52 upwardly within the valve unit 44 until the upper limit of such relative reciprocation is reached and the elements are in the relationship shown in Figure 2 with the upper end of the element 52 coplanar with the upper end of the valve unit 44 and the head 53 engaged against the lower end of the valve unit section 44a, in which position the ports 55 are closed to prevent further admission of steam from the compartment D to the upper end of the slide chamber, the exhaust passage from the upper end of the slide chamber to the exhaust line 48 remains open for escape of pressure from the slide chamber upper end and line 41 communicating therewith, for consequent opening of valve 36 and closing of valve 43 and resulting reestablishment of water flow through the supply line 34, and ports 61 are obstructed to close the vent passage therethrough and thus add the pressure effect of steam within the lower end of the slide chamber to the forces tending to move the valve unit 44 upwardly within the slide chamber. Further expansion of the element 31, aided by the pressure of the steam within the lower portion of the slide chamber and the pressure of water inflowing through the line 34 against the lower surface of the plate 46, operates to shift the valve unit 44 upwardly of the slide chamber 25 and to the upper limit of its range of travel while maintaining the element 52 at the upper limit of its relative reciprocation within said unit, and to the relationship of elements shown in Figure 3. During travel of the valve unit 44 upwardly within the slide chamber 25, the valve element 52 is held in closing relation with the ports 55 and with its ports 59 opening to the compartment E, so that the vent passage from the upper end of the slide chamber to and through the exhaust line 48 remains open for relief of pressure in the said upper end of the slide chamber and in the line 41, thus maintaining the valve 36 open and the valve 43 closed for inflow of water to the lower end of the slide chamber through the line 34. With the valve unit 44 at the upper limit of its range of travel, the compartment D is positioned to receive steam discharged from the line 47, which steam, because of lack of any outlet from said compartment, is trapped and held therein; the

compartment C is placed in communication with the lines 14 and 48 so that pressures obtaining in the ends of the barrel 11, branches 13 and line 14 may be relieved through the exhaust passage thus established to and through said exhaust line 48; the compartment B is placed in communication with the line 15 and branch steam line 49, so that steam under pressure inflowing through the branch 49 may pass through compartment B and line 15 to the space between the spool valves 18 and shift said valves to their respective outer ends of the barrel 11, where they are pressure-held in position to obstruct communication between the lines 23 and 24 and the interior of the housing 10; the compartment A is placed in registration with the port or ports 28, so that pressures obtaining within the housing 10 may be relieved through the exhaust passage thus established through said port or ports 28, compartment A, registering ports 62 and 63, bore 57, ports 60, compartment E, ports 54, compartment C, and exhaust line 48; the valve unit end section 44a is lifted out of covering relation with the discharge end of the line 50, thus permitting inflow of unheated water to the slide chamber portion surrounding the thermostatic element 31; and the plate 46 is positioned above the port or ports 29 to permit free inflow of feed water from the line 34, through the pipes 32 and port or ports 29 to the interior of the housing 10.

With the elements of the device positioned as shown in Figure 3, feed water delivered through the line 34 rises and accumulates within the reservoir defined by the housing 10, there being now no steam or entrapped air pressure within said housing to impede the inflow of water, while inflow of unheated water through the line 50 to the space about the element 31 operates to cool and contract said element with consequent downward travel of the associated valve element 52 relative to the valve unit 44, the latter being held at the upper limit of its range of travel during this phase of operation by pressure of the incoming feed water against the under surface of the plate 46.

Initial contraction of the element 31 draws the attached valve element 52 downwardly within the valve unit 44 until the shoulders 51 and 52c engage, and to the relationship of elements shown in Figure 4, in which position the ports 59 and 60 are obstructed and closed, thus closing the exhaust passage from the upper end of the slide chamber 25, and the ports 55 are uncovered to permit steam flow from compartment D, fed by line 47, into the upper end of the slide chamber and line 41 opening thereto, the pressure thus developed within line 41 operating to close valve 36 for interruption of feed water flow through line 34 and opening valve 43 controlling the by-pass 42.

As the element 31 continues to contract, the downward pull thus exerted on the valve element 52 acts through the engaged shoulders 51 and 52c to move the valve unit 44 downwardly against the pressure of the feed water below the plate 46, and the pressure of steam now present in the upper end of the slide chamber and acting against the upper ends of the said unit 44 and valve element 52 assists downward travel of the said unit and element to the extent necessary to fully overcome any water resistance developed against the plate 46 and to force any feed water entrapped within the lower end of the slide chamber beneath said plate back through the pipes 32, fitting 33, valve 43 and by-pass 42, until said plate 46 is again seated against the plug 26 in closing rela-

tion with the upper ends of the pipes 32, and the elements of the device are returned to the relationships shown in Figure 1, ready for automatic repetition of their operative cycle.

It is recognized that there probably will be some leakage of steam pressures along the walls of the barrel 11 and slide chamber 25 past the wall-engaging elements of the valves 18 and valve unit 44, but it is to be noted that such leakage will be, in every position of the valve elements, from a high pressure zone to a region, area or compartment in communication with the exhaust line 48, so that such leakage can in no instance be productive of operation-nullifying adverse or back pressures.

As will be apparent from the foregoing, the device thus far described is susceptible of normal, fully-automatic operation through a repetitive cycle to feed water to an operating boiler for maintenance of a determined water level therein. However, as a safe-guard against possible abnormalities, such as operative failure or rupture of the thermostatic element 31, auxiliary means is provided to warn of the abnormal condition and to continue supply of feed water, though at a slower rate, to the boiler served by the device.

The auxiliary means is illustrated as including a by-pass flow line 64 in closely-spaced, parallel relation with and below the bottom closure of the housing 10 and opening at one end through said bottom closure and into the interior of said housing; the other end of the line 64 opening upwardly within the lower end of a vertically-disposed, straight tube 65 of material having a relatively-high coefficient of thermal expansion. The tube 65 is fixed at its lower end to the closed lower end of, and is housed in spaced, axially-coincident relation within, an imperforate stand-pipe 66 which connects at its upper end with and is closed by a valve fitting 67 through which the steam line 47 serving the upper end of the slide chamber 25 communicates. The fitting 67 defines an interior chamber F spaced somewhat above the upper end of the stand-pipe 66, and said chamber is formed with opposed, conical, valve seats 68 and 69 in its upper and lower walls, respectively, and in axial coincidence with the projected axis of the tube 65. The supply portion of the steam line 47 opens into the chamber F through the valve seat 68, and the extension of said line 47 connects between any suitable point of the chamber side wall and the interior of the slide chamber 25 in the relation with the latter previously described. A double-acting valve plug 70 is housed within the chamber F and is formed with upper and lower, conical end portions adapted to selectively and respectively seat and close against the valve seats 68 and 69, the plug 70 being of a length less than the spacing between said seats, so that when the plug is closed against one of the seats, the passage communicating through the other seat is open. When the tube 65 is contracted to its length at normal temperatures, the upper end of said tube is spaced below the upper end of the stand-pipe 66 and adjacent portion of the fitting 67 such a distance as will allow for linear expansion of said tube when heated to the temperature of the boiler steam without engagement of the tube end against the fitting. The lower wall of the fitting 67 is intersected by a straight, two-diameter bore in axial alignment with the tube 65 and valve plug 70, the greater diameter portion of said bore opening through the valve seat 69 and the lesser diameter portion of said bore opening into the upper end

15

of the stand-pipe 66, and a stem 71 is slidably mounted in and for axial reciprocation relative to said bore in rigidly-connecting relation between the valve plug 70 and upper end of the tube 65, the length of said stem 71 being such as will serve to seat the lower end of said plug firmly against and in closing relation with the valve seat 69, and thereby open a passage through the valve seat 68 and compartment F through which steam may flow between the sections of the line 41, when the tube 65 is contracted to its length at normal temperatures, and seat the upper end of the valve plug 70 firmly against and in closing relation with the valve seat 68, thereby obstructing inflow of steam from the supply section of the line 41 to the compartment F while opening communication through the valve seat 69 between said compartment and the bore portion of greater diameter, when the tube 65 is extended in response to the effect thereon of higher temperatures. The bore portion of greater diameter beneath the valve seat 69 is operatively connected by means of a branch line 72 with the exhaust line 48, and a suitable flow line 73 connects said bore portion with a steam whistle 74, or like signal or signal-actuating device, so that warning of the presence of steam under pressure in the bore portion of greater diameter may be automatically given.

The auxiliary means illustrated and above described is designed to function when the level of feed water within the housing 10 falls, because of any operative failure or mal-functioning of the device, below the minimum level determined by the location of the by-pass flow line 64. During normal operation of the device, the feed water level in the housing 10 will rarely, if ever, drop below the line L—L of Figure 1, regardless of the water level in the boiler, since as soon as any portion of the port or ports 29 is uncovered, steam from the interior of the housing will enter the lower portion of the slide chamber, expand the element 31, and promptly initiate inflow of water to the housing from the line 34. However, should the element 31 fail to respond to the steam temperature, the movable valve elements of the device will remain in the relationships shown in Figure 1, wherein the tube 65 is contracted to hold the valve plug 70 in closing relation against the seat 69, until the outflow of feed water from the housing through the line 24 under the balancing pressure of steam inflowing to said housing through the line 23 lowers the feed water level in the housing to such a degree as will permit the steam in said housing to back the water trapped in the by-pass line 64 into the tube 65 and thence, through ports 75 opening through and adjacent the ends of said tube, into the stand-pipe 66, thus opening a passage through which the steam may enter said tube and stand-pipe. When subjected to the higher temperature of the steam, the tube 65 extends upwardly, lifting the plug 70 from the seat 69 and closing said plug against the seat 68, thus cutting off supply of steam through the line 41 to compartment F and opening an exhaust passage through said compartment, valve seat 69, branch line 72 and exhaust line 48, wherethrough pressures obtaining in compartment D, the upper end of slide chamber 25, line 41, and line 14 with its branches 13, may be relieved. Drop of pressure in line 41 results in opening of valve 36 and closing of valve 43 with consequent inflow of feed water through the line 34 against the under surface of plate 46.

16

An exhaust passage being now open, as above described, between compartment D and exhaust line 48, steam pressures previously obtaining in the upper end of the slide chamber 25 and line 5 and branches 14, 13 are relieved and the inflow of feed water against the under surface of plate 46 acts to lift said plate, together with the associated valve unit 44 and element 52 upwardly within the slide chamber 25 and to the relative position of said unit and element shown in Figure 4, any resistance to upward travel of the valve unit 44 being obviated by the passage open from the upper end of the slide chamber 25 through ports 55, compartment D, fitting 61, and branch line 72 to the exhaust line 48. With the valve unit 44 elevated to and held in the position shown in Figure 4 by the pressure of the inflowing feed water against the plate 46, compartment B of said unit is placed in simultaneous communication with lines 15 and 49 so that steam from the latter, which is connected with the supply portion of line 41 in by-passing relation with fitting 61, may flow through compartment B and line 15 to the interior of barrel 11 between the adjacent inner ends of the valves 18 and urge said valves apart and to the position shown in Figure 4, so that said valves obstruct and close off inflow of steam through the line 23 to an outflow of water through the line 24 from the housing 10. The line 14 and branches 13 being in direct communication through compartment C with exhaust line 48, there is no resistance to travel of the valves 18 outwardly within the barrel 11.

With the elements of the apparatus positioned as shown in Figure 4 through the agencies and operations hereinabove described, the plate 46 is disposed above the port or ports 29 and feed water from the line 34 may freely flow into and rise 35 within the reservoir of the housing 10, the only possible resistance to such charging of the reservoir being the pressure of steam entrapped therein. To obviate any adverse effect of such entrapped steam, a vent passage therefor is provided through the valve element 52, which passage is illustrated as including a central aperture in the baffle 58 between the element bores 56 and 40 57, and a check valve, such as a ball 76 yieldably 45 spring-urged downwardly into normal closing 50 relation with and against the upper end of said aperture, controlling passage through said aperture in a manner to permit transfer of fluid under pressure from the bore 57 to the bore 56, while inhibiting such transfer in the opposite direction. With the arrangement shown, steam 55 from the housing 10 may pass, when the elements of the apparatus are in the position shown in Figure 1 and after the tube 65 has expanded to position the valve 70 as shown in Figure 6, 60 into the lower portion of the slide chamber 25 through the port or ports 29, thence through the ports 61 to the bore 51 of the element 52, through the aperture of the baffle 58, lifting the valve ball 76, thence through the bore 56, ports 55, compartment D, and exhaust passage through the fitting 61 to the line 48. After the valve unit 44 65 has been lifted to the position of Figure 4 and incoming water has risen above the port or ports 29, the ports 63 of the valve unit being now in communication with the ports 28 of the slide chamber, a vent passage for the entrapped steam 70 may still be provided through said ports 28 and 63 by upward elongation of the ports 62 of the element 52 as indicated by broken lines in Figure 75 4, whereby said steam may pass from the upper

17

portion of the housing 10 into the bore 57 and thence escape to exhaust along the path above outlined.

With the valve unit 44 elevated by pressure of the inflowing feed water, the discharge end of the line 50 is uncovered to permit inflow of water through said line to the slide chamber 25 below said valve unit, thereby enhancing the rate at which the housing 10 is charged with feed water. Should it be the thermostatic element 31 that is 10 inoperative, inflow of cooling water through the line 50 has no effect on the position of the valve unit 44 and element 52, and supply of water to the reservoir of the housing 10 continues until the tube 65 cools and contracts sufficiently to 15 move the valve 70 to its normal operating position shown in Figure 1 and into opening relation with the steam line 47, whereupon steam is again permitted to flow through the sections of said line and into compartment D, thence through the 20 open ports 55 and open upper end of the valve unit into the line 41, where the pressure of said steam serves to close the valve 36 and open the valve 43. The steam pressure in the upper end of the valve unit 44 acts to urge said unit downwardly within the slide chamber and to the position of said unit shown in Figure 1, thus reestablishing the connections and relationships operable to shift the valves 18 inwardly of their barrel 25 for inflow of steam to the housing 10 through the line 23 and outflow of water from said housing and to the boiler through the line 24, thus completing the operative cycle of the apparatus. Should no correction of the malfunctioning of the device be immediately forthcoming, the device would continue to supply feed water to the boiler at a somewhat retarded rate, and would repetitiously actuate the warning signal, in the manner above set forth, thus safeguarding against dangerously rapid lowering of the water 30 level within the boiler.

As is indicated in the drawings, booster devices of injector type, conventionally illustrated at 77 and 78, may be operatively associated with the lines 24 and 50, respectively, and suitably connected into steam supply circuits through suitable manual controls, not shown, in a common manner to enhance and stimulate flow through said lines, when and as desired.

Since many changes, variations, and modifications in the specific form, construction and arrangement of the elements shown and described may be had without departing from the spirit of my invention, I wish to be understood as being limited solely by the scope of the appended 55 claims, rather than by any details of the illustrative showing and foregoing description.

I claim as my invention:

1. A boiler water feed device comprising, a feed water reservoir disposed for coplanar relation of its minimum contents level with the desired boiler water level, steam and water flow lines communicating between said reservoir and the boiler to be served, means for inflowing feed water to said reservoir, pressure-actuatable means and controls alternatively positionable to maintain the water-charged reservoir in pressure-balanced, gravity-flow relation with said boiler and to recharge said reservoir with feed water, a compound slide valve shiftable to direct and regulate 70 flow of fluid under pressure to said pressure-actuatable means, a temperature-responsive element in positioning relation with said slide valve, and means reactive to minimum reservoir contents level for exposing said element directly to 75

18

the elevated temperature steam charge of said reservoir.

2. A boiler water feed device comprising, a feed water reservoir disposed for coplanar relation of its minimum contents level with the desired boiler water level, steam and water flow lines communicating between said reservoir and the boiler to be served, feed water inflow means serving said reservoir, pressure-actuatable valves controlling said flow lines and said inflow means, pressure lines serving said valves, a compound slide valve shiftable to direct and regulate flow through said pressure lines, and temperature-responsive means reactive to direct contact with the reservoir steam and feed water charges to shift said slide valve and thereby position said pressure-actuatable valves for maintenance of the water-charged reservoir in pressure-balanced, gravity-flow relation with said boiler and to alternatively recharge said reservoir with feed water as a consequence of minimum contents level therein.

3. A boiler water feed device comprising, a feed water reservoir disposed for coplanar relation of its minimum contents level with the desired boiler water level, steam and water flow lines communicating, respectively, between upper and lower portions of said reservoir and the boiler to be served, pressure-actuatable valves controlling flow through said lines, pressure lines selectively serving said valves for simultaneous positioning thereof in either open or closed relation with their respective flow lines, feed water inflow means serving said reservoir, a pressure-actuatable valve controlling said inflow means, a pressure line serving said latter valve, a compound slide valve shiftable to direct and regulate flow through said pressure lines and temperature-responsive means reactive to direct contact with the reservoir steam and feed water charges to shift said slide valve and thereby position the pressure-actuatable valves for maintenance of the water-charged reservoir in pressure-balanced, gravity-flow relation with said boiler and to alternatively recharge said reservoir with feed water as a consequence of minimum contents level therein.

4. A boiler water feed device comprising, a feed water reservoir disposed for coplanar relation of its minimum contents level with the desired boiler water level, a steam pressure flow line connecting between the upper portion of said reservoir and the boiler to be served, a water flow line connecting for gravity flow of water between the lower portion of said reservoir and the boiler to be served, pressure-shiftable valves controlling flow through said lines, pressure means common to and serving both said valves for simultaneous positioning thereof in corresponding open or closed relation with their respectively associated flow lines, means including a compound slide valve actuatable as a consequence of minimum contents level in said reservoir to adjust said pressure means for simultaneous closing of both said flow lines, means for the automatic inflow of water to said reservoir while said flow lines are closed, and means operable in correlation with said water inflow to automatically shift said slide valve and thereby readjust said pressure means for interruption of said inflow and to simultaneously open both said flow lines when the said reservoir is water-charged.

5. In a boiler water feed device having a feed water reservoir disposed for coplanar relation of its minimum contents level with the desired boiler water level and means for the inflow of

19

said reservoir, means for establishing pressure-balanced, gravity-flow communication between said reservoir and the boiler to be served and alternatively closing said communication during inflow of water to the reservoir, said means comprising a straight, tubular, closed barrel vertically intersecting and extending at each end beyond said reservoir, a steam flow line connecting between the upper barrel extension and the boiler, a water flow line connecting between the lower barrel extension and the boiler, ports intersecting the barrel walls interiorly and closely adjacent the top and bottom walls of the reservoir, separate, like valve members slidably cooperating with opposite portions of said barrel to open communication through said barrel between each of said flow lines and the adjacent barrel ports when said valve members are at the inner limit of their range of travel relative to said barrel and to close communication between said lines and their adjacent ports when said valve members are at the outer limit of their range of travel, pressure means selectively operable to simultaneously position said valve members at one or the other of their limits of travel, a pressure-actuatable valve controlling said water inflow means and temperature-responsive means and associated controls automatically operable as a consequence of minimum contents level in said reservoir to position and hold said valve members at the outer limit of their range of travel and to simultaneously open a path for water inflow through said pressure-actuatable valve and to subsequently close said water inflow path and simultaneously shift said valve members to the inner limit of their range of travel when said reservoir is water-charged.

6. Apparatus as set forth in claim 5 wherein said valve members are of double-spool type and each includes annular end heads and an intermediate annular rib adapted to slidably coat with the barrel walls, and cylindrical sections of reduced diameter connecting between said rib and heads, whereof the section disposed outwardly of the barrel has a length adequate to bridge over the space between its associated flow line and adjacent barrel port.

7. Apparatus as set forth in claim 5, wherein said pressure means includes a branched pressure line opening through and simultaneously serving opposite ends of the barrel and alternatively connectible with a pressure supply line or an exhaust to atmosphere, and a separate pressure line serving the midportion of the barrel between the valve members and alternatively connectible in flow relation opposite to that of said branched line with a pressure supply line or an exhaust to atmosphere.

8. Apparatus as set forth in claim 5 wherein said pressure-actuatable valve includes a pressure chamber, a pressure-reactive element in said chamber, a plunger connected to said pressure-reactive element and reciprocable therewith into and out of closing relation with a water flow line, and resiliently-yieldable means normally holding said pressure-reactive element and associated plunger in open relation of the latter with the water flow line, and a pressure flow line alternatively connectible with a pressure supply line or an exhaust to atmosphere serving said pressure chamber.

9. Apparatus as set forth in claim 5, wherein said temperature-responsive means and associated controls are housed in a slide chamber altitudinally traversing and projecting upwardly be-

20

yond the reservoir and include an heat-extensible element arranged for reaction to the steam in said reservoir when the water level therein subsides to a predetermined minimum, a compound valve assembly shiftably associated with said element, and exhaust, pressure flow, and pressure supply lines opening into said slide chamber for automatically variable operative interconnection through the agency of said valve assembly.

10. In a boiler water feed device having a feed water reservoir disposed for coplanar relation of its minimum contents level with the desired boiler water level, steam and water flow lines between said reservoir and the boiler to be served, simultaneously-actuatable, pressure-responsive valves correspondingly controlling flow through said lines, means for the inflow of feed water to said reservoir, a pressure-responsive valve controlling said inflow means, and pressure flow lines serving said valves, means automatically operable as a consequence of minimum water level in said reservoir to close said reservoir steam and water flow lines and open said inflow means and to subsequently open said reservoir steam and water flow lines and close said inflow means when the reservoir is water-charged, said means comprising a slide chamber altitudinally traversing and projecting upwardly beyond said reservoir, an heat-extensible element in the lower portion of said chamber, ports in the lower slide chamber wall exposible at minimum reservoir water level to permit passage of steam from said reservoir to the slide chamber portion housing said element, a compound valve assembly slidably cooperating with the upper slide chamber portion and shiftably associated with said element, connections between said pressure flow lines and the upper slide chamber portion, a pressure supply line, an exhaust line, and a cold water supply line serving said slide chamber, and means inherent in the valve assembly construction positionable as a consequence of element extension to interconnect said pressure flow, pressure supply, and exhaust lines for closing of said reservoir steam and water flow lines, opening of said water inflow means, and to establish inflow through said cold water supply line, and alternatively positionable as a consequence of element contraction to reverse the flow relations previously established.

11. Apparatus as set forth in claim 10, wherein the pressure flow, pressure supply, exhaust, and cold water supply lines open through the slide chamber walls in altitudinally spaced relation and the means inherent in the valve assembly construction alternatively positionable to selectively interconnect certain of said lines consists of a plurality of annular ribs integral with and spaced altitudinally along a valve assembly unit in slidable engagement with the slide chamber walls to limit and define annular compartments about reduced-diameter sections of said unit.

12. Apparatus as set forth in claim 10, wherein the compound valve assembly comprises a cylindrical, multi-spool type unit formed with a two-diameter axial bore, a two-diameter element slidably within said bore for limited reciprocation relative to said unit, a head on the lesser end of said element engageable at times with the adjacent end of said unit to limit travel of said element relative to said unit in one direction, alternatively registrable openings through the walls of said unit and element, and means securing said head to the upper end of the heat-extensible element.

13. Apparatus as set forth in claim 10, wherein

21

the feed water inflow means delivers through the lower end of the slide chamber and the compound valve assembly carries in fixed association a plate reciprocable altitudinally of the slide chamber lower portion disposed to close over and obstruct the delivery end of the water inflow means when said valve assembly is at the lower limit of its range of actuation within the slide chamber.

14. Apparatus as set forth in claim 10, wherein the feed water inflow means includes a return water flow line connected with the inflow line in by-passing relation with the pressure-responsive inflow control valve, a pressure-responsive valve controlling communication between said return and inflow lines adjacent the delivery end of the latter, and pressure means simultaneously serving both of saids valve for selective actuation thereof in maintained opposite flow-controlling relation with their respective lines.

15. Apparatus as set forth in claim 10, wherein in the cold water supply line opens for discharge through the slide chamber wall above the heat-extensible element and in flow-obstructing relation against a lower portion of the slide compound valve assembly when said element is contracted, and is thus positioned and arranged for automatic delivery of cold water against and about said element as a consequence of element extension and resulting upward shifting of the valve assembly.

16. In a boiler water feed device having a feed water reservoir disposed for coplanar relation of its operative predetermined minimum water level with the desired boiler water level, steam and water flow connections between said reservoir and the boiler to be served, and means for inflowing

22

water to said reservoir, pressure-actuatable, temperature-responsive means and controls automatically cooperable to maintain the water-charged reservoir in pressure-balanced, gravity-flow relation with said boiler and to recharge said reservoir with feed water when the water level therein reaches its predetermined operative minimum, and supplementary temperature-responsive means operable to correspondingly control said pressure-actuatable means in response to a lowering of the reservoir water level beyond the predetermined operative minimum as a consequence of failure or malfunctioning of said first-named temperature-responsive means and controls.

17. Apparatus as set forth in claim 16, wherein the pressure-actuatable, temperature-responsive means and controls are served by a pressure flow line alternatively connectible with a pressure supply line and an exhaust to atmosphere, and said supplementary temperature-responsive means comprises a valve shiftable to selectively connect said flow line with said supply line or exhaust, an heat-extensible element fixed at one end and connected at its movable end with said valve to close said exhaust and open communication between said flow line and supply line when said element is contracted and to close said supply line and open communication between said flow line and exhaust when said element is heat-extended, and means exposable through lowering of water level in the reservoir below a predetermined operative minimum to conduct steam from said reservoir to and for heating effect on said element.

THOMAS N. PINION.
